UNITED STATES PATENT OFFICE

120,228

DESIGN FOR A STOCKING

Paul R. Nestler, Green Lane, Pa.

Application March 13, 1939, Serial No. 83,536

Term of patent 3½ years

To all whom it may concern:

Be it known that I, Paul R. Nestler, citizen of the United States of America, residing at Green Lane, in the county of Montgomery and State of Pennsylvania, have invented a new, original, and ornamental Design for a Stocking, of which the following is a specification, reference being had to the accompanying drawing, forming part thereof, in which:

Fig. 1 is a side elevation of a stocking, showing my new design.

Fig. 2 is an enlarged fragmentary part of the stocking shown in Fig. 1.

I claim:

The ornamental design for a stocking, as shown.

PAUL R. NESTLER.
